Charles W. Hoffmann INVENTOR

BY
Theadore H. Farbman, ATTORNEYS

UNITED STATES PATENT OFFICE.

CHARLES W. HOTTMANN, OF PHILADELPHIA, PENNSYLVANIA.

STUFFER.

Application filed October 8, 1921. Serial No. 506,274.

To all whom it may concern:

Be it known that I, CHARLES W. HOTTMANN, a citizen of the United States, residing at Philadelphia, county of Philadelphia, 5 State of Pennsylvania, have invented a new and useful Stuffer, of which the following is a specification.

The object of my present invention is to devise a novel construction and arrangement of a stuffer wherein the material will be fed continuously from the stuffer under a substantially uniform pressure.

Other objects of my invention are to provide a simple and compact machine which 15 can be maintained in a sanitary condition and wherein the material is fed under pressure to a rotary stuffing element which will effect the discharge from the stuffer of a predetermined quantity of material.

With the above and other objects in view which will hereinafter appear my invention comprehends a novel construction and arrangement of a stuffer.

It further comprehends a novel construction of a stuffer having a casing provided with a novel construction and arrangement of agitating and scraping members and from which the material is discharged to feeding mechanism which feeds the material under 30 pressure through a restricted port into a chamber communicating with the discharge spout and in which is contained a novel construction of material delivering mechanism.

Other novel features of construction and 35 advantage will hereinafter more clearly appear in the detailed description.

For the purpose of illustrating my invention, I have shown in the accompanying drawings a typical embodiment thereof 40 which is at present preferred by me since this embodiment will be found in practice to give satisfactory and reliable results. It is, however, to be understood that the various instrumentalities of which my invention 45 consists can be variously arranged and organized and that my invention is not limited to the precise arrangement and organization of these instrumentalities as herein shown and described.

Figure 1 represents a top plan view of a 50 stuffer, embodying my invention.

Figure 2 represents a section on line 2—2 of Figure 1.

Figure 3 represents a section on line 3—3 55 of Figure 1.

Figure 4 represents a section on line 4—4 of Figure 2.

Figure 5 represents a section on line 5—5 of Figure 1.

Figure 6 represents a top plan view of a 60 partition.

Similar numerals of reference indicate corresponding parts.

Referring to the drawings.

1 designates the supporting framework, 65 the construction and arrangement of which may vary widely in practice.

2 designates the driving shaft which is provided with a pulley 3 in order to adapt it to be driven by any desired source of 70 power. The driving shaft 3 has fixed to it a pinion 4 which meshes with a gear 5 fixed to a feed shaft 6, which is journalled in a feed casing 7. 8 designates a container for the material and this container is provided 75 in its bottom with a discharge opening 9 communicating with a chamber 10 of the feed casing 7. The feed chamber 10 has one of its walls in proximity to the discharge opening 9 inclined or bevelled, as indicated 80 at 11, see Figure 5. The feed shaft 6 has mounted on it in the feed chamber 10 a helical blade 12 which serves as a conveyor and which at its forward end closely fits the reduced bore 13 of the feed chamber 10, so 85 that the proper pressure is exerted against the material as it is being fed through such reduced bore 13.

The feed chamber 10 at its forward end is 90 of enlarged diameter, as seen at 14, and the chamber thus formed is separated from the main body portion of the feed chamber 10 by means of a stationary partition 15 which is in the form of a ring segment having its 95 ends spaced from each other a desired distance to form with the wall of the feed chamber 10 a discharge port 16.

The feed shaft 6 has keyed to it at its forward end a stuffing member 17 in the form of a cylindrical block having projecting from its periphery a plurality of blades 18, see more particularly Figures 3 and 4. The feed casing 7 at its delivery end terminates in a delivery spout 19, the bottom wall of which in proximity to the stuffing member 17 is inclined 100 downwardly and outwardly, as at 20, and then turned upwardly, as at 21.

22 designates a blade fulcrumed at 23 and having its forward end adapted to ride on the periphery of the stuffing member 17 and 110

be retained thereagainst by means of a spring 24. The casing 8 has disposed centrally within it a bearing sleeve 25 which is flanged at its lower end in order to adapt it 5 to be connected to the bottom of the casing 8 by means of fastening devices 26. The sleeve carries at its upper end a bearing 27 through which passes a shaft 28, the lower end of which is mounted in a step bearing 29.

30 designates a worm gear which meshes with a worm 31 on the driving shaft 2. Secured to the shaft 28 by means of a key 32 is an agitator and scraper 33 having vertically 15 disposed blades 34 which at their bottom are laterally deflected, as at 35, to ride on the bottom of the container 8 and the laterally extending portions 35 are upwardly deflected as at 36, so that they extend the desired distance 20 above the container 8. The forward end of the feed chamber 10 is closed by means of a closure 37.

The operation of my novel stuffer will now be apparent and is as follows:—

25 The material to be stuffed is placed in the container 8 preferably during the revolution of the driving shaft 2. The worm 31 and the worm gear 30 cause the shaft 28 to revolve and thereby the agitating and scraping members 34 which cause the material in 30 the container 8 to feed towards and into the discharge opening 9 and therethrough into the feed chamber 10. The feed shaft 6 which is intergeared with the driving 35 shaft 2 causes the material to be fed forwardly in the feed chamber 10 into the restricted bore 13 so that the desired pressure is created on such material and the material then passes through the port 16 into the 40 chamber formed between the blades 18, the periphery of the stuffing member 17 and the juxtaposed wall of the casing.

Each blade 18 during its revolution brings a predetermined amount of material into the 45 discharge spout 19 and therefrom into the casing which is to be stuffed, the casing being connected with such spout in any desired or conventional manner. The material is prevented from feeding backwards into 50 the opening 16 by the blade 22 which rides on the periphery of the stuffing member 17, the blades 18 being so constructed that during their rotation they will move the blade 22 outwardly and pass therebeneath.

55 It will be seen that the feeding members 34 move in close proximity to the juxtaposed walls of the container 8 so that a slow feed due to the worm drive of the material towards the discharge opening 9 is brought 60 about.

It will now be apparent that I have devised a novel and useful stuffer which embodies the features of advantage enumerated as desirable in the statement of the invention and the above description, and while I 65

have, in the present instance, shown and described an embodiment thereof which will give in practice satisfactory and reliable results, it is to be understood that said embodiment is susceptible of modification in 70 various particulars without departing from the spirit or scope of the invention or sacrificing any of its advantages.

Having thus described my invention, what I claim as new and desire to secure by 75 Letters Patent, is:—

1. In a stuffer, a casing having a discharge opening, rotary material circulating means in said casing, means to feed the material from said opening and compress it 80 during such feed, and means to effect the discharge from said stuffer of a predetermined amount of compressed material.

2. In a stuffer, a casing having a discharge opening, means to effect a circulation 85 of the material in said casing toward said discharge opening, means to feed the material from said discharge opening and compress it during such feed, and rotary means to effect the discharge from such stuffer of 90 a predetermined amount of compressed material.

3. In a stuffer, a stationary casing having a discharge opening, means to circulate the material to and from said opening, a feed 95 chamber communicating with said discharge opening, a conveyor in said feed chamber to effect the feed and compression of the material, and a rotary member to which the compressed material is fed and adapted to 100 continuously feed predetermined amounts of compressed material from said stuffer.

4. In a stuffer, a stationary casing, a feed casing having a chamber communicating therewith, and provided with a reduced bore 105 at its discharge end a feed screw in said feed casing extending into said reduced bore and adapted to feed the material in a longitudinal path, and a rotary stuffing member to which the material is fed by said 110 feed screw.

5. In a stuffer, a casing for the material, a feed casing communicating with said casing, a ported member dividing said feed casing into two compartments, a feed screw 115 in one compartment, a rotary stuffing member in the other compartment and actuated by said feed screw, and means to actuate said feed screw.

6. In a stuffer, a casing for the material 120 having a discharge opening in its bottom, a feed casing communicating with said opening, a ported member dividing said feed casing into two compartments, a feed screw in one of said compartments, a rotary stuffing member having spaced blades in the other of said compartments and actuated by 125 and in unison with said feed screw, and means to actuate said feed screw.

7. In a stuffer, a casing for the material, 130

a feed casing communicating at its rear end with said first casing, a ported member dividing said feed casing into two compartments, a feed screw in one of said compartments, said casing having a reduced diameter to receive the forward end of said feed screw to thereby cause the material being fed to be compressed, a rotary stuffing member in the other of said compartments and actuated by said feed screw, said casing having a delivery spout to which the material is fed by said stuffing member, and means to actuate said feed screw.

8. In a stuffer, a casing for the material, a feed casing communicating at its rear end with said first casing, a ported member dividing said feed casing into two compartments, a feed screw in one of said compartments, said casing having a reduced diameter to receive the forward end of said feed screw to thereby cause the material being

fed to be compressed, a rotary stuffing member in the other of said compartments and actuated by said feed screw, said casing having a delivery spout and means to cause 25 said stuffing member to deliver the material into said stuffing spout.

9. In a stuffer, a feed casing having an inlet opening at one end for the material, a rotary feed member in said casing, said 30 casing having a side delivery opening at its opposite end, a stuffing member to which the material is fed by said rotary member and rotated by said member to feed the material into said side opening, resilient means 35 to prevent a backward pressure on the material being fed, and means to actuate said feed member.

CHARLES W. HOTTMANN.
